DRAFT AND BUFFER GEAR

George A. Johnson, Chicago, Ill., assignor to W. H. Miner, Inc., Chicago, Ill., a corporation of Delaware

Application June 2, 1933, Serial No. 673,983

14 Claims. (Cl. 213—9)

This invention relates to improvements in draft and buffer gears especially adapted for mine cars.

One object of the invention is to provide a simple and efficient combined draft and buffer gear for mine cars, wherein means is employed for absorbing shocks and this means is so arranged as to receive the actuating force directly from a buffering head against which the shock absorbing means is compressed in draft through lever mechanism connected to the usual coupling means of the car.

Another object of the invention is to provide, in a gear of the character set forth in the preceding paragraph, lever means so arranged and designed that the shock absorbing means is compressed in draft to substantially the same extent it is compressed in buff.

Other objects of the invention will more clearly appear from the description and claims hereinafter following.

In the drawing, forming a part of this specification, Figure 1 is an elevational view, partly broken away, of one end of a mine car, illustrating my improvements in connection therewith.

Figure 2 is a part plan view and part horizontal sectional view of Figure 1, the section being taken on the line 2—2 of Figure 1. Figure 3 is a vertical sectional view, corresponding substantially to the line 3—3 of Figure 1. And Figure 4 is a part side elevational view and part vertical sectional view of Figure 1, looking toward the left in said figure, the section being taken on the line 4—4 of Figure 1.

In said drawing, 10 indicates the end sill member of a mine car, which carries my improved draft and buffer gear.

My improved gear comprises broadly a support A; a buffering head B; a draft yoke C; a lever D for transmitting the draft forces from the yoke 40 C to the shock absorbing means of the gear; a pair of shock absorbing springs E—E cushioning both the draft and buffering forces; and a pair of buffering springs F—F.

The support A, which is preferably a casting, 45 forms a housing for the other parts of the gear. The support A may be in the form of a separate member attached to the end sill of the car, or may be formed as a part of the end sill casting 10, as illustrated in the drawing. The support 50 A has a vertical rear wall 11 which, as shown, forms a continuation of the casting 10. The wall 11 is provided with forwardly projecting, spaced side walls 12—12, a horizontal bottom wall 13, and a top wall 14. At the bottom portion of the support A, the side walls 12—12 are

outwardly offset with respect to the upper sections of said walls, as clearly shown in Figure 1, thereby providing intermediate horizontal wall sections 15—15. The lower portions of the side walls 12—12, the bottom wall 13, and the wall sections 15—15 project forwardly beyond the upper sections of the side walls 12—12, as shown in Figures 3 and 4. The bottom wall 13 of the support A is reduced in thickness between its ends, thereby presenting relatively thickened portions 16—16 at opposite sides of the support A. The thickened portions 16—16 present top flat guide surfaces for slidingly supporting the buffering head B. The top wall 14 of the support A has a down-turned front section 17 forming a relatively short front wall which is rounded at the inner lower corner, as indicated at 18 in Figures 3 and 4. Beyond the rounded section 18, the wall 17 projects outwardly of the upper sections of the side walls 12—12, as clearly shown in Figures 3 and 4. The front wall section 17, the top wall 14, and the upper end portion of the rear wall 11 together define a pocket or bearing seat 19 for the upper end of the lever D.

The buffering head B is in the form of a casting 25 having a vertical front wall 20, spaced vertical side walls 21—21, and spaced top and bottom walls 22—22. The outer surface of the wall 20 is rounded, as shown in Figure 2, and presents a buffering surface which directly cooperates with the buffering head of the adjacent car. The head B has the inner end thereof telescoped within the housing between the bottom wall 13 and the wall sections 15—15. The head B is thus mounted for inward sliding movement on the support A.

The draft yoke C comprises top and bottom arms 23 and 24 connected at their rear ends by vertically disposed, laterally spaced webs 25—25. At the rear end, the yoke C is cut away, as indicated at 26, so that clearance is provided for upward tilting of the yoke under certain operating conditions. At opposite sides, the yoke is provided with trunnions 27—27, which serve to connect the yoke to the lever D. As most clearly shown in Figure 3, the yoke C is directly supported on the top wall 22 of the buffer head B and has sliding contact therewith. A coupling pin 28, which extends through vertically aligned slots 29—29 in the top and bottom arms 23 and 24 of the yoke and through vertically aligned slots 30—30 in the top and bottom walls 22—22 of the buffering head B, serves as a connection between the usual coupling link and the yoke C, whereby the draft forces are transmitted to the gear.

The lever D, which transmits the draft forces from the yoke C to the shock absorbing means of the gear, is in the form of a casting having a pocketed follower member 31 at the lower end thereof, a transverse upper end section 32, and spaced side arms 33-33 connecting the follower member 31 to the end section 32. The side arms 33-33 are so spaced as to accommodate the inner end of the yoke C therebetween. Substantially midway between the upper and lower ends, the lever D has the side arms 33-33 thereof provided with interior bearing seats 34-34, which accommodate the trunnions 27-27 at opposite sides of the yoke C. The upper end of the lever D is rounded, as clearly shown in Figures 3 and 4, so as to have pivotal movement in the pocket 19 of the support A. The upper end section 32 of the lever has a flat front face, which has rocking engagement with the wall section 17 of the pocket 19 of the support A. As clearly shown in Figures 3 and 4, the bearing seats 34-34 of the arms 33-33 of the lever D open rearwardly so as to permit easy assembling of the yoke C and lever D by entering the trunnions 27-27 through said openings of the seats 34-34. The lever D is directly supported on the buffer head B, the arms 33-33 of the lever being provided with forwardly projecting flanges 35-35, which bear directly on the top wall 22 of the head B. The inner end section of the yoke C rests directly on the follower member 31 of the lever D and is supported thereby, as clearly indicated in Figure 3.

The shock absorbing springs E-E are arranged centrally of the mechanism and are interposed between the front wall 20 of the buffer head B and the rear wall of the follower member 31 of the lever D and bear directly on these walls.

The pair of buffer springs F-F are disposed at opposite sides of the springs E-E and bear at their front ends on the front wall 20 of the buffer head B and at their rear ends directly on the rear wall 11 of the support A. Outward movement of the buffering head B is limited by stop pins or bolts 36-36 extending through aligned slots 37-37 in the top and bottom walls 22-22 of the buffer head B and aligned openings in the bottom wall 13 and the intermediate wall sections 15-15 of the support A.

The operation of my improved draft and buffer gear is as follows: Upon a pulling action being applied to the yoke C through the coupling pin 28, the yoke is moved outwardly away from the end of the car, thereby rocking the lever about its upper end in the pocket 19 of the support A. The bottom end of the lever D is thus pulled forwardly, compressing the springs E-E against the buffering head B, which at this time is held stationary by the stop pins 36-36. If the pull of the draft member is at an angle in an upward direction, the yoke will readily accommodate itself to such displacement through the clearance provided by cutting away the upper section of the rear end of the yoke, as hereinbefore pointed out. During its swinging movement, the lever D is directly supported on the buffering head B and rocks about its pivoted upper end on the walls 14 and 17 and the rounded section 18 of the wall 17, thereby providing a smooth easy action during the operation of the device.

Upon a buffering force being applied to the head B, both pairs of springs E-E and F-F will be compressed. The springs E-E are compressed against the follower member 31 of the lever D,

the lever at this time being held stationary by engagement of the rear face of the follower member 31 with the rear wall 11 of the support A. The springs F-F are directly compressed against the rear wall 11.

I have herein shown and described what I now consider the preferred manner of carrying out my invention, but the same is merely illustrative and I contemplate all changes and modifications that come within the scope of the claims appended hereto.

I claim:

1. In a combined draft and buffer gear for cars, the combination with a buffer head at the end of the car slidably supported for movement inwardly toward said end of the car; of a shock absorbing means opposing inward movement of said head; a draft member movable away from the car; a lever movably supported on said buffering head, said lever being pivotally supported at its upper end and having the lower end thereof engaging the shock absorbing means to compress the same in draft; and means operatively connecting the draft member to the lever.

2. In combined draft and buffer gear for cars, the combination with a buffer head at the end of the car slidably supported for movement inwardly toward said end of the car; of a shock absorbing means opposing inward movement of said head; a draft member movable away from the car; and a pivoted lever swingable about its upper end and having its lower end engaging the shock absorbing means to compress the same in draft, said lever being movably supported on the buffering head and connected between its ends to the draft member.

3. In a combined draft and buffer gear for cars, the combination with a buffer head at the end of the car supported for movement inwardly toward the car; of shock absorbing means opposing inward movement of said head; an upright swinging lever; means pivotally supporting said lever at one end and holding the same against upward displacement, said lever having the opposite end portion thereof engaging the shock absorbing means to compress the same during outward movement of the lever in draft; fixed abutment means for holding said last named end portion of the lever against inward movement during a buffering action of the gear; and a draft member pivotally connected to the lever between the ends of the latter.

4. In a combined draft and buffer gear for cars, the combination with a buffer head at the end of the car supported for movement inwardly toward said end; of shock absorbing means opposing inward movement of said head; an upright lever having abutment means at its lower end engaging said shock absorbing means; a bearing member on which the upper end of said lever is pivoted, said bearing member holding the lever against upward displacement; and a draft member pivotally connected to the lever at a point between the pivoted upper end and the abutment means thereof.

5. In a combined draft and buffer gear for cars, the combination with a support at the end of the car; of a buffer head slidably inwardly on said support; shock absorbing means yielding opposing said inward movement of the head; an upright lever engaging the shock absorbing means to compress the same against the buffering head, said lever being supported on the buffering head; and a draft member pivotally connected to the lever at a point between the pivoted upper end and the abutment means thereof.

nected to the lever, said lever having rocking engagement at its upper end with said support.

6. In a combined draft and buffer gear for cars, the combination with a supporting member 5 on the end of the car; of a buffer head slideable inwardly on said member; a lever in rocking bearing engagement at its upper end with said member, said lever having follower means at its lower end; means on said lever above said fol- 10 lower means movably supporting the lever on the buffer head; shock absorbing means inter- posed between and bearing on the buffer head and follower means; and a draft member slide- 15 able on the buffer head, said draft member be- ing pivoted to the lever between the upper end of the lever and the follower means thereof.

7. In a combined draft and buffer gear for 20 cars, the combination with a supporting casting at the end of the car, said casting having a ver- 25 tically disposed rear wall; of a downwardly open- ing bearing pocket at the top end of said cast- 30 ing, said pocket having a top wall and a front wall, the lower portion of the front wall thereof being rounded; a buffer head slideable inwardly 35 on said casting; a draft member above said head; a lever supported on the head having its upper end extending into said bearing pocket and normally engaging the top and front walls of 40 said pocket; follower means at the lower end of 45 said lever, said follower means normally bearing on the vertical wall of the casting; shock ab- 50 sorbing means interposed between the lever and the buffer head; and means between the ends of 55 the lever pivotally connecting the same to the draft member.

8. In a combined draft and buffer gear for 60 cars, the combination with a supporting casting at the end of the car, said casting having a downwardly facing bearing pocket at the top 65 thereof; of a buffer head slideably supported on the casting; a draft member above said head; a lever movably supported on said head and hav- 70 ing its upper end loosely engaged within said pocket for rocking movement and held against upward displacement by engagement with a wall 75 of said pocket; follower means on the lower end of the lever; shock absorbing means interposed between and bearing on the follower means and buffer head; and means between the ends of the 80 lever pivotally connecting the draft member to the lever.

9. In a combined draft and buffer gear for 85 cars, the combination with a supporting housing at the end of the car, said housing having hori- 90 zontal guide means at the bottom and a bearing pocket at the top; of a buffer head slideably supported on said guide means; a lever movably supported on said head, said lever having its upper end swiveled in said pocket and held 95 against upward displacement by engagement with a wall of said pocket; a draft member pivotally connected to the lever below said swiveled end; follower means on the lever below said piv- 100 otal connection with the draft member; and shock absorbing means interposed between and bearing on said follower means and buffer head.

10. In a combined draft and buffer gear for 105 cars, the combination with a supporting housing at the end of the car, said housing having a 110 horizontal guideway at the bottom and a pocket at the top; of a buffer head slideably supported in said guideway; a draft member slideably sup- 115 ported on the buffer head; an upright lever having follower means at its lower end and a

flange above said follower means slidably sup- 110 porting the lever on the buffer head, the upper end of said lever extending into said pocket and having pivotal movement therein; means be- 115 tween the ends of the lever pivotally connecting the same to the draft member; and shock ab- 120 sorbing means yieldingly opposing relative move- 125 ment of the buffer head and follower means of the lever.

11. In a combined draft and buffer gear for 130 cars, the combination with a support fixed to 135 the end of the car; of a buffing head movable inwardly on said support; an upright lever piv- 140 oted at one end to swing on said support, said pivoted end having shouldered engagement with 145 the support to hold said lever against upward displacement; cushioning means embraced be- 150 tween the other end of said lever and said buff- 155 ing head, said cushioning means being com- 160 pressed between said lever and buffing head upon 165 relative movement of said lever and head; and 170 a pulling element connected to said lever be- 175 tween the ends of the latter.

12. In a combined draft and buffer gear for 180 cars, the combination with a support fixed to the 185 end of the car, said support having a shoulder thereon provided with a downwardly facing bear- 190 ing surface; of a buffing head movable on said support in a direction lengthwise of the car; an 195 upright lever having the upper extremity thereof rounded and bearing on said surface; stop means 200 on said support against which the lever normally bears to hold said lever against movement to- 205 ward said end of the car; a pulling element con- 210 nected to the lever between the ends of the latter 215 to swing the lower end of said lever away from the end of the car; and cushioning means em- 220 braced between said last named end of the lever and the buffing head, said cushioning means 225 bearing at opposite ends respectively on the in- 230 nner side of the buffing head and the forward side 235 of said last named end of the lever.

13. In a combined draft and buffer gear for 240 cars, the combination with a support on the end 245 of the car; of a buffer head slideably mounted on said support; shock absorbing means yielding- 250 ly opposing movement of said head; a draft mem- 255 ber; an upright lever swiveled between its ends to the draft member for transmitting the draft 260 force from the draft member to the shock ab- 265 sorbing means; means for holding said lever against upward displacement, comprising a bear- 270 ing member against which the upper end of the lever bears and on which said lever is pivoted, said lever at a point below said swiveled connec- 275 tion engaging with the shock absorbing means; and a fixed stop, means on the car engaged by 280 said lever for holding the latter against inward 285 movement during a buffing action of the gear.

14. In a combined draft and buffer gear for 290 cars, the combination with a support at the end 295 of the car; of a buffer head movably mounted on said support, said head being movable in- 300 wardly toward the car in buff; stop means for 305 holding said head against outward movement in draft; an upright lever swingable about its upper end; a draft member pivotally connected to the lever below the upper end thereof; and shock absorbing means interposed between the 310 buffer head and the lever and engaging the lever 315 at a point below the pivotal connection thereof 320 with the draft member.
